UNITED STATES PATENT OFFICE.

WILLIAM H. FOSTER, OF BAYSIDE, NEW YORK.

JOURNAL-BOX.

1,342,164.

Specification of Letters Patent. Patented June 1, 1920.

Application filed October 22, 1919. Serial No. 332,383.

To all whom it may concern:

Be it known that I, WILLIAM H. FOSTER, of Bayside, in the county of Queens and State of New York, have invented a certain 5 new and useful Improvement in Journal-Boxes, of which improvement the following is a specification.

My invention relates to the ordinary type of journal boxes for the axles of railroad 10 vehicles, in which type, lubrication is effected by oil supplied to the journal from a packing of fibrous or porous material, as cotton waste, which is fitted in the journal box, below, and in contact with, the axle journal 15 which rotates therein. The object of my invention is to prevent the seriously objectionable heating of the journal which frequently occurs in service; the leakage of oil from the journal box; and the displacement 20 of the packing, by effecting a constant circulation of air through the journal box during the running periods of the vehicle on which it is fitted; preventing the access of oil to the joint between the box and its lid; 25 and holding the fibrous packing in normal relation to the journal.

The improvement claimed is hereinafter fully set forth.

In the accompanying drawings: Figure 1 30 is a vertical longitudinal central section through a journal box, illustrating an embodiment of my invention; Fig. 2, a horizontal section through the same, on the line *a a* of Fig. 1; Fig. 3, a view, partly in front 35 elevation and partly in vertical transverse section, on the line *b b* of Fig. 1; and Fig. 4, a similar section, illustrating a structural modification.

In the practice of my invention, referring 40 descriptively to the specific embodiment thereof in connection with a journal box, 1, of the Master Car Builders' type, which is herein exemplified, the journal box is, as heretofore, fitted with a hinged lid, 2, closing 45 an opening in its front for the insertion and removal of packing. The front end of the journal box is provided, adjacent to the opening therein, with an inwardly and downwardly projecting deflecting plate, 3, 50 having lateral ribs or flanges, 3^a, projecting from its inner face, formed on, or fixed to, the lid, with its bottom about in line horizontally with, or somewhat below, the axial line of the journal, 4. I have found that, 55 in practice, oil is thrown up from the packing, by centrifugal force, from the periph-

ery of the end collar, 4^a, of the axle, and tends to follow down the inside of the lid, and leak out through the opening covered by the lid. It has been shown, by tests, that 60 by the application of the deflecting plate, the oil which is thrown toward the top of the box, is caused to pass down on the inside of the deflecting plate and drip off into the box, without leakage therefrom, this action being facilitated by the side flanges of 65 the plate, which prevent the oil from running off its sides and therefrom to the sides of the lid. A material saving of oil, which would otherwise be wasted, is accordingly 70 effected.

A longitudinally extending air channel, 5, which is open at both ends, is formed on, or fixed to, the outer side of the box lid, 2, said channel communicating with an adjoining closed ended suction chamber, 5^a, through an opening, 5^b, the suction chamber communicating, in turn, with the interior of the journal box, through an opening, 5^c, in the lid, located a short distance below the 80 upper end of the deflecting plate, 3. In the movement of the vehicle on which the journal box is installed, the current of air passing through the channel, 5, acts to draw air out of the suction chamber and the communicating interior of the journal box, the air withdrawn being replaced by fresh air leaking into the inner end of the box. This circulation of cool air through the journal box prevents the heating of the air therein, 85 which would be liable to occur if the air was permitted to remain quiescent therein, as in ordinary practice, and correspondingly reduces the liability to heating of the journal. 90

In order to insure the fibrous packing of 95 the journal box being retained longitudinally in normal position therein, a plurality of upwardly projecting teeth or packing retainers, 6, is formed on the inside of the bottom wall of the journal box, said teeth being 100 preferably, as shown, disposed in two longitudinal rows, and being curved or inclined toward the inner end of the box, so as not to interfere with the free insertion of the packing, and to resist its accidental and undesired movement, from its normal position 105 toward the front end of the box.

It will be seen that the application of my invention does not involve any departure 110 from the form and manner of connection of the journal boxes and lids of present standard practice, nor involve the use of any

additional or separate members requiring bolted or riveted connections. The construction is, further, simple and inexpensive, and adds no appreciable weight to the 5 ordinary journal box.

I claim as my invention and desire to secure by Letters Patent:

1. The combination of a journal box having an opening in its outer end; a lid, normally closing said opening; and an inwardly and downwardly projecting deflecting plate, fixed on the inner side of said lid. 10
2. The combination of a journal box having an opening in its outer end; a lid, normally closing said opening; an inwardly and downwardly projecting deflector plate, fixed on the inner side of said lid; and lateral flanges, projecting upwardly from said deflecting plate. 15
3. The combination of a journal box provided with a lid, having a ventilating opening, of a deflector plate fixed on the inside of said lid, above said opening and adapted to extend below the same, providing a shield 20
- 25 therefor, to prevent the splashing of oil and dirt into said opening.

4. The combination of a journal box provided with a lid, having a ventilating opening, of a deflector plate fixed on the inside of said lid, above said opening and adapted to extend below the same, providing a shield 30 therefor, to prevent the splashing of oil and dirt into said opening, and prevent also the oil from being thrown out from around the lid during the active use of the journal box. 35

5. The combination of a journal box, having an opening in its outer end, a lid, normally closing said opening, a ventilating passage-way carried by said lid, an aperture in said lid connecting the said passage-way 40 with the inside of the journal box, a downwardly projecting deflector plate fixed on the inner side of the lid above said aperture and extending below said aperture, providing a shield therefor, to prevent the splashing of oil and dirt into said ventilating passage-way. 45
